UNITED STATES PATENT OFFICE.

GLEN M. DYE, OF MINNEAPOLIS, MINNESOTA.

PHOTOGRAPHIC-DEVELOPING APPARATUS AND METHOD.

Application filed September 13, 1919. Serial No. 323,593.

To all whom it may concern:

Be it known that I, GLEN M. DYE, a citizen of the United States, residing at Minneapolis, in the county of Hennepin and State of Minnesota, have invented certain new and useful Improvements in Photographic-Developing Apparatus and Methods; and I do hereby declare the following to be a full, clear, and exact description of the invention, such as will enable others skilled in the art to which it appertains to make and use the same.

My invention has for its object to provide a method and apparatus for automatically performing all of the operations required for the complete development of photographic films and prints; and to such ends, generally stated, the invention consists of the novel method and the devices and combinations of devices hereinafter described and defined in the claims.

As is well known, the complete development of photographic films and prints involves several treatments or operations specifically designated as developing, rinsing, fixing, washing and drying. In carrying out these operations, the films and prints have usually been transferred by hand from the one place to the other where the several operations are performed, but in accordance with my invention, these operations are all automatically carried out by an apparatus involving a traveling carrier for the films or prints. In connection with the carrier, there are what may be designated as loading, developing, rinsing, fixing, washing and drying zones through which the carrier passes the films or prints in a regular order of succession. In the developing zone there is means for producing a continuous spray of the developing liquid on the films conveyed by the carrier; in the rinsing zone there is means for producing a spray of water on the developed films to wash the surplus developing material therefrom; in the fixing zone there is means for producing a spray of the hypo or fixing liquid on the rinsed films or prints; and in the washing zone there is means for delivering the spray of water on said films or prints. In the preferred arrangement of the apparatus, there is means for producing a blast of warm dry air on the films or prints to dry the same. The loading, developing, rinsing, and fixing zones will preferably be in the dark room so

that the films or prints will not be exposed to actinic light rays. The invention, however, involves various other highly important features, as will be hereinafter disclosed and claimed. For convenience of expression in the following description and in the claims, the film or photographic print will be referred to as "film," but it will be understood that this term is intended to cover any one of the said articles, or any other sheet or plate coated with the sensitized emulsion.

The improved apparatus is illustrated in the accompanying drawings wherein like characters indicate like parts throughout the several views. Referring to the drawings:

Fig. 1 is a view in horizontal section illustrating the photo-developing apparatus, some parts being in diagram;

Fig. 2 is a front elevation of the apparatus shown in Fig. 1, the floor on which it is mounted being in section and some parts being removed;

Fig. 3 is an enlarged horizontal section taken approximately on the lines 3—3 of Figs. 2 and 5, some parts that are above said line being shown in full and by dotted lines and some parts being broken away;

Fig. 4 is a similar view to Fig. 3, but illustrating different positions of the parts;

Fig. 5 is a vertical section taken approximately on the lines 5—5 of Figs. 1 and 3;

Fig. 6 is a transverse vertical section taken approximately on the line 6—6 of Fig. 2;

Fig. 7 is a fragmentary perspective showing a portion of the film carrier and intermediate associated parts;

Fig. 8 is an enlarged horizontal section taken approximately on the line 8—8 of Fig. 2;

Fig. 9 is a side elevation of the mechanism shown in Fig. 8, some parts being removed;

Fig. 10 is a view similar to Fig. 8, but illustrating a modified mechanism; and

Fig. 11 is a horizontal section illustrating a modified arrangement in which a pre-washer is provided.

The apparatus illustrated in Figs. 1 to 9, inclusive, will first be described. The mechanism of my improved apparatus is arranged partly within and partly outside of a dark room, and usually the light and dark rooms will be separated by a wall or partition 13 extended from a floor 14. The film carrier which is preferably in the form of

- an endless sprocket chain or link belt, is arranged to travel in a horizontal plane through and along the opposite sides of the partition 13 and, as shown, the sprocket 5 chain 15 which affords said carrier, is arranged to travel over sprocket wheels 16 and 17 that are located in film passage-ways 18 and 19, respectively, formed in the said partition and extended down quite close to the floor or far enough to permit the film to pass therethrough when suspended from said sprocket chain or carrier belt. Said sprockets 16 and 17 (see particularly Fig. 8), are journaled to suitable bearings on 10 the partition 13, and the shaft of the sprocket 16 is shown as provided with a worm gear 20. Worm gear 20 meshes with a worm 21 on a shaft 22 journaled in suitable bearings 23 fixed to the partition 13. 15 At its extended end, shaft 22 has a face friction wheel 24 with which co-operates a peripheral friction wheel 25 that is carried by, but slidably on a small counter shaft 26, journaled in suitable bearings on a supporting bracket 27 secured to partition 13 (see particularly Figs. 2, 8 and 9). Friction wheel 25 is adapted to be adjusted radially of friction wheel 24, and thereby set for the transmission of different speeds, by an adjusting lever 28 pivoted to bracket 27. At 20 its outer end, shaft 26 has a sheave 29. A belt 30 runs over sheave 29 and over a sheave 31 on the armature shaft of a small electric motor 32 shown as supported on the bracket 27. By the means just above described, the link belt 15 is adapted to be continuously driven at any desired speed from motor 32. 25 In the drawings, the films in the form of film strips γ are arranged to be spaced apart and carried by the carrier belt 15, and the said belt is provided with means for detachably holding the same, and preferably also, for detachably holding order number tabs γ^1 . This means, as shown, comprises upper metal arms 33 secured to certain of the links of said belt and provided at their lower ends with flat plate-like heads 34 equipped with spring clamps 35 for directly gripping the upper edges of the films. At 30 their upper ends, said arms 33 are shown as provided with flat plates 36 to which the order tabs γ^1 may be detachably secured by spring clips 37, or the like. 35 To support the carrier belt between sprockets, the arms 33 are shown as provided with forwardly and rearwardly projecting rider pins 38 that are arranged to travel over laterally spaced parallel horizontally extended rails 39. Said rails 39 40 are located in pairs on opposite sides of the wall 13 and, as shown, are rigidly secured to the prongs of inverted U-shaped hanger brackets 40, which, in turn, are rigidly secured to the said wall 13 (see particularly Figs. 5 and 6). These rails receive the rider pins 38 as they pass from the one sprocket and guide the same to the other sprocket, and this, as already indicated, takes place on both sides of the wall 13. 45 The film and the order number tabs will be applied to the carrier on that portion of the chain that is moving through the loading zone marked A on Fig. 1. From loading zone A, the films will be carried through developing zone B, thence, through rinsing zone C, thence, through fixing zone D, and thence through washing zone E. From washing zone E, Fig. 1, the films will be carried through the rear opening of the wall 13, thence through drying zone F and 50 thence through unloading zone G, from which latter, the fully developed films will be removed, all as will hereinafter more fully appear. The carrier, in passing from unloading zone G to loading zone A moves 55 through a housing 41 which is of such construction as to exclude light from the dark room side of the wall. In developing zone B, at the lower portion thereof, there is a large catch pan or open top tank 42 that 60 contains the developing liquid. The bottom of this tank is connected by a return pipe 43 to a pump 44 which has a discharge pipe 45 that extends upward in the said developing zone B and is provided with a plurality of vertically spaced laterally extended spray pipes 46. These spray pipes 46 are perforated on one side (see particularly Fig. 6) so that they are adapted to project intersecting sprays over the entire 65 surfaces of all of the films that are within said developing zone. Upright pipe 45 has a laterally offset vertical branch pipe 47 that is located approximately at the place where the films pass from the loading zone A into the developing zone B. This branch pipe 47 is provided with vertically spaced perforations adapted to throw intersecting sprays directly onto the films approximately 70 as they enter the developing zone. 75 In it is highly important that the films have their entire surfaces simultaneously covered with the developing liquid in order to prevent uneven or spotted development thereof. Hence, I provide in connection with the initial spray pipe 47, a movable shield and co-operating means whereby the films will first 80 enter the developing zone, and will be protected from the initial spray of developing liquid until they have reached a position where, by a sudden dash, the initial spray may be thrown over the entire surface thereof. This device, as shown, comprises a shield 48 which is pivoted on pipe 47, and at 85 its upper edge is provided with an extended arm 49. A hood 50 fixed on and in respect to pipe 47, encloses said pipe and shields and prevents outward splashing of the developing liquid. At its lower extremity, this hood 50 has a depending flange 90

51 that directs the liquid dashed against the same, into the open tank 42 (see particularly Fig. 5). A curtain 52 located in the developing zone B and hung 5 at its upper edge from bracket 40 and other suitable supports, stops that part of the spray that is not stopped by the films and directs the same back into the tank 42.

A coiled spring 53 shown as attached to 10 arm 49 and hood 50 tends to hold the movable shield 48 into the position shown in Fig. 4. The free end of arm 49, however, projects in the path of movement of the upper portions of the film metal arms 33, so 15 that it will be immediately engaged thereby. When the arm 49 is engaged by one of the arms 33, it will be moved approximately to the position shown in Fig. 3, thereby carrying the shield into position indicated in Fig. 20 3. When the shield is moved from its position shown in Fig. 4 toward the position shown in Fig. 3, it will cut off the sprays projected from the initial spray pipe 47 and will prevent such sprays from reaching the 25 film until the film has totally entered in the developing zone, and thereupon, the arm 49 will be released and spring 53 will quickly throw the same back to the position where it will engage a fixed stop 49^a of the hood 50, 30 as shown in Fig. 4, and this will cause the sprays from the said pipe 47 to be simultaneously thrown over the entire surface of a film, as clearly shown in Fig. 4, thereby insuring instantaneous covering of the sensitized surface or emulsion of the film and 35 even development thereof.

At the lower portion of rinsing zone C is a catch pan 54 which has a discharge pipe 55. For spraying the developed film with clear 40 water in this zone C, there is an upright water supply pipe 56 which has lateral spray pipes 57 perforated so as to project intersecting sprays on the films as they are carried through the rinsing zone C by the carrier 45 belt. This water pipe 56 may be connected to any suitable source of water supply, such as a city water main.

Located in the lower portion of fixing zone D is a large catch pan or open top tank 58. 50 The bottom of this tank 58 is connected by a pipe 59 to a pump 60 which has an upright discharge pipe 61 provided with vertically spaced laterally projecting spray pipes 62 that are perforated so as to project intersecting sprays on the films as they are carried through the fixing zone by the endless carrier belt. Here it may be stated that the pumps 44 and 60 are preferably rotary pumps which may be driven by any suitable 55 means, but as shown, are individually driven by small electric motors 44^a and 60^a, respectively. The purpose of the pumps in the constructions described, is to produce a continuous circulation of the developing and 60 fixing liquids. Where city water service is

used, as in the rinsing and washing zones, saving of water is not necessary, and hence, circulating pumps are not necessary.

In the lower portion of the washing zone E is a large catch pan 63 which has a discharge pipe 64. Extended upward in the washing zone is a water supply pipe 65 which has a plurality of vertically spaced laterally projecting spray pipes 66 provided with perforations adapted to throw intersecting sprays of water on the films as they pass from the fixing zone.

In the drawings, the ends of spray pipes 46, 57, 62 and 66 are shown as resting on small brackets 67 secured on vertical supporting posts 68.

As the washed films pass from washing zone E, they are carried through the opening 19 in wall 13 and through the drying zone F. The drying zone is within a housing 69 secured to wall 13. This housing is open at its top, but at the bottom is connected by short air tubes 70, to a hot air pipe 71, which, in practice, will be connected to a suitable source of hot or warm air supply, 90 such as a fan connected, in turn, to a heating chamber.

The operation already generally indicated may be briefly summarized, as follows:

The films y, at their upper ends, are attached to the continuously traveling carrier belt by the clips 35 as they pass through the loading zone A. To cause the film to hang straight down, clip-like weights 72 may be applied to the lower ends thereof. 100 From loading zone A, the films pass in regular order through the developing zone B where they are first given the initial dash spray from pipe 47, as already described, and from thence, they pass through the spray of developing liquid discharged thereon from the horizontal spraying pipes 46. The time interval required for the films to pass through the developing zone will be sufficient to cause the proper development 110 of the negative thereon. From the developing zone, the films pass through rinsing zone C where the surplus developing liquid is washed therefrom, and from thence, they pass into and through a fixing zone D where 115 the time interval required for the films to pass through the fixing zone D and during which they will be subjected to the continuous spray of the fixing liquid or hypo, will be sufficient to effect the proper fixing of the negative. From the fixing zone D, films pass through the washing zone where the surplus fixing liquid will be washed from the films. Next, the films pass through the long housing 69 of the drying zone F where 120 they are subject to the currents of warm air so that when the films pass from the drying zone they will be dried and fit for removal as they are carried into the unloading zone G. In this way, all of the opera- 125 130

tions incident to complete development of the films are accomplished automatically, the only hand operations being those required to attach the films to the carrier belt and to 5 remove the same therefrom.

This machine is capable of rapidly turning out a large number of films and is, therefore, especially adapted for use where a very large amount of film development is to be 10 done and where small cost per film is of high importance.

As already indicated, this apparatus or machine may be used for complete development of either negatives, using the term in 15 the ordinary sense, or what are usually designated as photographic prints, post cards, or the like, having photo-sensitive faces on which pictures are printed.

Figs. 10 and 11 illustrate modified arrangements which permit the initial dash spray for the films as they enter the developing chamber, to be dispensed with. Fig 10, for example, illustrates means for giving the carrier belt an intermittent movement, so 20 that the films will be moved completely within the developing zone by a quick movement. In this arrangement, sprocket wheel 16, in lieu of worm gear 20, is provided with ratchet wheel 73, and this ratchet wheel is 25 operated on by a driving dog 74 carried by a lever 75 pivoted on the shaft of said gear 16. Lever 75 is connected by a link 76 to a crank pin carried by a worm gear 77 that meshes with a power driven worm 78.

35 In Fig. 11, the prewashing device, which is located in advance of developing zone B, comprises a vertical water supply pipe 79 having laterally projecting perforated spraying pipes 80 that direct the spray of water directly onto the films as they pass from the loading zone and before they pass into the developing zone. This prewashing device wets the sensitized faces of the 40 films so that the developing liquid sprayed thereon in the developing zone will be caused to completely spread over the sensitized surface thereof, and thus avoid spotting or uneven developing. Of course, the sensitive face of the film must be placed 45 toward the spray. The continuous circulation of the developing and fixing liquid keeps the same well stirred up and active and insures maximum acceleration of the developing processes. Moreover, the continuous spray or shower against the emulsion coated or sensitive faces of the film or 50 print keeps the same clear of dust and prevents spotting from such sources.

The air for drying purposes should not 55 be hot but quite warm and dry.

What I claim is:

1. In a photographic developing apparatus, a carrier for the films arranged to carry the films past developing and fixing zones, 60 and spraying means in said developing and

fixing zones operative to spray the sensitized surfaces of the films, respectively, with the developing and fixing liquids.

2. In a photographic developing apparatus, and endless traveling film carrier, developing and fixing zones past which the films are carried by said carrier, catch pans in the lower portions of said developing and fixing zones located below the line of travel of the films, spraying pipes in said 70 developing and fixing zones for delivering sprays of developing and fixing liquid on films as they pass, respectively through said developing and fixing zones, and circulating connections between said catch pans and the respective spraying pipes for maintaining a circulation of the respective liquids therethrough.

3. In a photographic developing apparatus, a carrier for the films arranged to carry 85 the films past developing and fixing zones, spraying means in said developing and fixing zones operative to spray the sensitized surfaces of the films, respectively, with the developing and fixing liquids, and the said 90 spraying means in the developing zone comprising an initial spraying device operative intermittently and with a dashing action on the entered films.

4. In a photographic developing apparatus, a carrier for the films arranged to carry the films past developing and fixing zones, spraying means in said developing and fixing zones operative to spray the sensitized surfaces of the films, respectively, 100 with the developing and fixing liquids, said spraying means in the developing zone comprising an upright spraying pipe and a carrier actuated oscillatory shield acting to intermittently throw an initial spray against 105 the entering films with a sudden action.

5. In a photographic developing apparatus, an endless horizontally movable film carrier arranged to carry the films progressively from loading, past developing, rinsing, fixing and washing zones, means in the developing zone for automatically spraying the films with the developing liquid, means in the rinsing zone for spraying the developed films with water, means in the fixing zone for spraying the rinsed films with a fixing liquid, and means in said washing zone for spraying the fixed films with water.

6. In a photographic developing apparatus, an endless horizontally movable film carrier arranged to carry the films progressively from loading, past developing, rinsing, fixing and washing zones, means in the developing zone for automatically spraying the films with the developing liquid, means in the rinsing zone for spraying the developed films with water, means in the fixing zone for spraying the rinsed films with a fixing liquid, means in said washing zone for spraying the fixed films with water,

the said spraying means in said developing and fixing zones including spray pipes, drip pans, power driven pumps, and liquid circulating connections between the respective 5 pans, pumps and spraying pipes.

7. In a photographic developing apparatus, the combination with a horizontally movable endless carrying belt and guide wheels therefor, of power driven means for 10 imparting traveling movement to said belt, said carrier belt having a film clamping device and being arranged to carry the films progressively from loading, past developing, rinsing, fixing and washing zones, of spraying devices in said developing, rinsing, fixing and washing zones arranged to spray the films with the proper liquids.

8. In a photographic developing apparatus, the combination with a horizontally 20 movable endless carrying belt and guide wheels therefor, of power driven means for imparting traveling movement to said belt, said carrier belt having a film clamping device and being arranged to carry the films 25 progressively from loading, past developing, rinsing, fixing and washing zones, of spraying devices in said developing, rinsing, fixing and washing zones arranged to spray the films with the proper liquids.

30 said carrier belt, on its opposite sides having projecting rider pins, and rails extending between said sprockets and on which said rider pins are arranged to slide.

9. In a photographic developing apparatus, the combination with a horizontally 35 movable endless carrying belt and guide wheels therefor, of power driven means for imparting traveling movement to said belt, said carrier belt having a film clamping device and being arranged to carry the films 40 progressively from loading, past developing, rinsing, fixing and washing zones, of spraying devices in said developing, rinsing, fixing and washing zones arranged to spray the films with the proper liquids, the said 45 carrier belt having holders for order tabs associated with each film clamp.

10. The method of handling photographic

films which consists in suspending the films 50 from a traveling carrier, continuously and uniformly moving said carrier and films through developing, rinsing, fixing and washing zones, spraying said films with developing, rinsing, fixing, and washing solutions, respectively, while moving through 55 said respective zones, and subsequently moving said films through a drying chamber.

11. The method of handling photographic films which consists in connecting the films 60 at one end to a traveling carrier so that the films depend vertically from said carrier, moving said carrier and films continuously in one direction and in spraying said films successively with developing and rinsing liquids during their continued movement in one direction.

12. The process set forth in claim 11, and spraying the films with fixing and washing liquids during their continued movement in 70 one direction.

13. The process set forth in claim 12, and continuing the movement of the films and carrier through a drying chamber.

14. The method of handling a photographic film which consists in suspending 75 the same from one end on a traveling carrier continuously and uniformly moving said carrier and film and spraying the same with a developing liquid.

15. The method of handling a photographic film which consists in suspending the same from one end in a dark room and uniformly advancing the same in one direction and spraying said film with developing 80 liquid.

16. The method of handling photographic films which consists in suspending the same from one end on a traveling carrier and continuously and uniformly moving said carrier in a horizontal plane through zones 85 in which the film is successively acted upon by developing, rinsing, fixing, washing and drying mediums.

In testimony whereof I affix my signature.

GLEN M. DYE.
